(57) **CLAIM**

The ornamental design for a slim rectangular tabletop mirror with embedded rectangular frosted lighting as shown and described.

DESCRIPTION

FIG. 1 is a front perspective view for a first embodiment of the slim rectangular tabletop mirror with embedded rectangular frosted lighting;

FIG. 2 is a bottom view of the first embodiment;

FIG. 3 is a front view of the first embodiment;

FIG. 4 is a left view of the first embodiment;

FIG. 5 is a right view of the first embodiment;

FIG. 6 is a back view of the first embodiment;

FIG. 7 is a top view of the first embodiment;

FIG. 8 is a front perspective view for a second embodiment of the slim rectangular tabletop mirror with embedded rectangular frosted lighting;

FIG. 9 is a bottom view of the second embodiment;

FIG. 10 is a front view of the second embodiment;

FIG. 11 is a left view of the second embodiment;

FIG. 12 is a right view of the second embodiment;

FIG. 13 is a back view of the second embodiment;

FIG. 14 is a top view of the second embodiment;

FIG. 15 is a front perspective view for a third embodiment of the slim rectangular tabletop mirror with embedded rectangular frosted lighting;

FIG. 16 is a bottom view of the third embodiment;

FIG. 17 is a front view of the third embodiment;

FIG. 18 is a left view of the third embodiment;

FIG. 19 is a right view of the third embodiment;

FIG. 20 is a back view of the third embodiment; and,

FIG. 21 is a top view of the third embodiment.

The broken lines depict portions of the slim rectangular tabletop mirror with embedded rectangular frosted lighting that form no part of the claimed design.

1 Claim, 21 Drawing Sheets
